ATTORNEY

UNITED STATES PATENT OFFICE.

HENRY CARL STAHL, OF POMPEYS PILLAR, MONTANA.

COMBINED UMBRELLA STAND AND PEDESTAL.

1,336,321.

Specification of Letters Patent.

Patented Apr. 6, 1920.

Application filed August 10, 1917. Serial No. 185,543.

To all whom it may concern:

Be it known that I, HENRY C. STAHL, a citizen of the United States, residing at Pompeys Pillar, in the county of Yellow-
stone and State of Montana, have invented
5 new and useful Improvements in Combined
Umbrella Stands and Pedestals, of which
the following is a specification.

This invention relates to a combined um-
10 brella stand and pedestal and the object is
to provide a device which may be employed
for receiving umbrellas to be dried, and
which may also be employed for storing
umbrellas when not in use.

15 A further object is to provide a device of
the character indicated useful as an article
of furniture and which may be employed
as a pedestal.

With the foregoing and other objects in
20 view, the invention consists in the novel con-
struction, combination and arrangement of
elements hereinafter described and claimed.

In the accompanying drawings—

25 Figure 1 is a perspective view showing
the cover open, and the umbrella supporting
arms in operative position.

Fig. 2 is a vertical section.

Fig. 3 is a detail view showing a portion
30 of one of the grooved strips, these strips re-
ceiving the slideable arms for directly sup-
porting the umbrella.

This device includes a base portion 10
having mounted thereon a standard 12 com-
prising a plurality of side members 13 fitted
35 together and forming a tapering member
constituting the umbrella stand proper. A
molding 14 may be provided above the base
and around the side members 13. The up-
40 per transverse member 16 is of suitable size
to give the device as a whole an artistic ap-
pearance and this member constitutes a
cover which is hinged at 17 and which may
be raised when umbrellas already in a dry
condition, are to be stored within the device

described. The height will be sufficient to 45
readily accommodate umbrellas of various
sizes. A molding 18 may also be provided,
being located as shown, and serving to
mount and support the cover and to support
the arms when the latter are open or ex- 50
tended.

A plurality of arms 20 are mounted for
slidable movement within the grooved strips
21 located as shown, the strips being notched
at 22.

55 The groove and notch of each strip being
of the relative size illustrated in Fig. 3, the
headed ends of the arms 20 are prevented
from accidental displacement from the
grooves. In the use of the device for dry- 60
ing umbrellas, the arms 20 are drawn up-
wardly and outwardly, the handle of the
umbrella being received within the pedestal
proper. After the drying operation the
arms are moved inwardly and downwardly, 65
the umbrella is closed and placed within the
pedestal, the top or cover of the latter then
being closed.

What is claimed is:

An article of furniture comprising a 70
standard forming a storage receptacle, a
flat base portion, a cover for the receptacle,
occupying a horizontal position when
closed, a molding surrounding the upper
edges of the walls of the receptacle, means 75
for hinging the cover to the molding,
grooved guiding strips within the standard
and adjacent to the walls thereof, and a
plurality of umbrella supporting arms mov-
able vertically within the grooves of the 80
strips, and upwardly and outwardly with
reference to the standard, to an approxi-
mately horizontal operative position, the
molding supporting the arms when ex-
tended, and supporting the cover when the 85
latter is closed.

In testimony whereof I affix my signature.

HENRY CARL STAHL.
